WILBUR L. WRIGHT, OF FULTON, NEW YORK, ASSIGNOR TO OSWEGO FALLS CORPORATION, OF FULTON, NEW YORK, A CORPORATION OF NEW YORK

TAPERED PAPER CONTAINER

Application filed June 27, 1928. Serial No. 288,596.

The essential purpose of this invention is to render more certain the liquid tight qualities of the bottom closures of paper containers, particularly those of tapered or so-called 5 conical form, and to so form the container bottom and bottom closure as to stiffen and strengthen the same against blows or pressure tending to so distort or deform the container as to destroy or partially destroy the 10 liquid tight qualities of the joint between the container body and its bottom closure, and those skilled in the art will readily understand the purpose and object of the invention in the light of the following explanations of the accompanying drawings that illustrate what I now believe to be the preferred 15 mechanical expressions or embodiments of my invention from among other forms within the spirit and scope thereof.

With the foregoing and other objects in view my invention consists in certain novel features and cooperating formations and elements as more particularly described and specified hereinafter.

Referring to the accompanying drawings forming part hereof:—

Fig. 1 shows in part an upwardly-converging tapered mandrel and a plunger in side elevation, and the small end portion of a tapered paper container barrel or body and a smooth-cut oversize inner stiff paper disk in vertical section, the upper end of the barrel being expanded and the disk seated against an annular ledge in the barrel by the plunger 30 after being driven through said end by the plunger.

Fig. 2 is a similar view with the exception that an oversize annularly-flanged outer paper disk is shown in vertical section driven 40 by the plunger through the expanded end and tightly pressed against the inner disk.

Fig. 3 shows the mandrel in side elevation, and in vertical section shows the paper barrel and inner and outer disks and a rim forming 45 and disk securing crimp, as well as the crimping or spinning head in vertical section.

Fig. 4 shows a tapered or frustro-conical paper container or bottle embodying my invention and partially broken away, the paper 50 container of this figure of the drawing show-

ing the bottom closure in the large end of the tapered barrel, whereas Fig. 3 shows the same in the small end of the paper barrel.

Fig. 5 is a detail vertical section of the structure of Fig. 4 on an enlarged scale.

The conical or tapered paper containers disclosed comprise a paper barrel that is longitudinally tapered from a large end to a small end.

One end of this paper barrel constitutes 60 the open top or mouth of the container, that is adapted to receive a removable closure.

The other end of the paper barrel is provided with a permanent bottom closure including an overlarge inside stiff smooth-cut 65 disk 3, and an overlarge outside annularly flanged disk 4, and this bottom structure involves a rim-forming and bottom closure-securing crimp, and a peculiar formation of the lower end of the paper barrel, all designed to render the container liquid tight 70 at its lower end and to strengthen the bottom closure against damage tending to break the liquid tight joint or seal.

The mouth of the container can be at 75 either the large or small end of the tapered barrel and consequently the bottom closure can be at either the small or large end of said barrel.

The paper barrel 1, of the container is preferably formed by a flat blank of strong stiff yet flexible sheet paper wrapped around or otherwise shaped on a tapered mandrel to the required tapered form with the longitudinal edges of the blank overlapping and permanently sealed and secured together to form 80 liquid tight longitudinal seam 1^a, throughout the length of the tapered body.

The upper end of this tapered body or barrel 1, is preferably formed to provide the 90 container with a top rim and mouth usually either by applying a neck ring thereto to provide a seat for a removable closure, or by spinning or crimping the upper end of the body outwardly and downwardly, or otherwise to provide a surrounding rim to receive a slip cover for the container.

The bottom end of the tapered barrel when first formed is overlong, see 1^c. This open tapered bottom end of the barrel, in the 100

method of bottoming the same, is forcibly enlarged in diameter from its large extremity inwardly a suitable distance longitudinally towards the opposite end of the barrel, by 5 outwardly stretching and expanding the sheet paper to approximately cylindrical form of enlarged diameter. By thus expanding the tapered barrel end, an annular outwardly facing intermediate internal ledge or shoulder 10 2, is formed in the barrel connecting the expanded end of the barrel and the undisturbed tapered portion thereof of relatively reduced diameter. A stiff strong usually heavy imperforate paper or like fibrous material disk 15 3, of enlarged diameter with respect to said tapered portion of the barrel and said ledge is driven longitudinally into the barrel through said bottom end while held in a position transversely of and at right angles to the longitudinal axis of the tapered body and while backed by the driving plunger throughout the area of the outer surface of the disk, and this disk is thus driven in and forcibly sealed against said ledge or shoulder with the annular portion of the inner side face of the disk 20 25 tightly fitting the ledge and the peripheral edge of the disk tightly fitting the inner surrounding surface of the enlarged end of the barrel where it merges into the ledge, all to 30 form a tight seal.

The essential characteristic of this stiff flat or slightly dished disk 3, is its smooth-cut cylindrical peripheral smooth-surface edge 3^a. This smooth-surface surrounding cylindrical edge of the oversize stiff or heavy disk 35 performs a peculiarly advantageous function in that it establishes a liquid tight joint by its intimate tight contact with the surrounding inner surface of the expanded end of the 40 paper body or barrel in cooperation with the annular liquid tight seal or joint established by and between the enlarged annular ledge and the inner sideface of the disk, and this last mentioned joint is concentric with and 45 continues inwardly toward the interior of the container from the tight joint or seal at the smooth peripheral edge of the disk. This smooth cut disk also cooperates with other features and the flanged disk 4, in establishing 50 a liquid tight bottom and in stiffening and strengthening the bottom structure.

The outer disk 4, is preferably struck up from more or less thin flexible sheet paper material to provide the disk with an annular 55 depending skirt or flange 4^a. This disk 4, is imperforate and its exterior diameter, in the plane of the flat body portion of the disk, is as near as possible the same as the exterior diameter of the heavy inner disk 3. This 60 flanged disk 4, is also driven into the expanded bottom end of the otherwise tapered container barrel preferably by a plunger that maintains the flat body of the disk in a plane perpendicular to the longitudinal axis of the body, while contacting or backing the flat

center or body of said disk throughout the area of its outer side. The flanged disk with its flange directed outwardly and preferably tightly held surrounding the driving plunger, is thus forced and driven into the container body end and forcibly pressed and seated against and into parallelism with the outer face of the disk 3, and the two disks are thus forced toward the ledge 2, against which the disk 3, is seated under comparatively heavy 75 pressure.

The forcing plunger is then removed, leaving the two tightly engaging parallel disks swaged into the container body end that is expanded thereby with the disk 3, tight 80 against the ledge 2, and the flange 4^a fitting tightly within and concentric with the outer expanded end of the body, and preferably terminating short thereof.

Thereupon, the projecting expanded end 85 of the body with the flange 4^a, therein, is turned, rolled or crimped inwardly and downwardly and subjected to inward longitudinal pressure, forming preferably locked, crimp 5, to permanently lock and hold the two disks 90 and ledge 2, drawn tightly together and the expanded wall of the container body drawn radially in tightly against the smooth cylindrical edge of disk 3, and against the outer surface of disk 4, and its flange 4^a, to thus immovably support said disks and secure the disks and container body fixedly together. This multi-ply crimp 5, also provides the container with a stiffening strengthening annular depending rim, whereby the bottom 100 disks are inset within the container body, and this rim is not only depending but forms the lower end of the body with a surrounding annular approximately exteriorly-cylindrical stiff rigid enlarged rim 5^a, by reason of the two overlarge interior parallel disks 3, 4, and the expanded body end surrounding said disks and turned in and up against the bottom of the flanged disk and holding the same and the inner disk tightly against and longitudinally immovable with respect to ledge 2.

This stiff strong enlarged diameter surrounding and depending bottom rim serves to strengthen the lower end of the container against distortion and indenting under handling by blows and pressures, that might otherwise tend to separate or break the liquid tight joints or seals between the disks and ledge 2, and the disks and surrounding expanded body wall. The barrel tapers upwardly from the ledge or shoulder 2, and this annular radially or outwardly projecting shoulder 2, joins the tapered portion with the end rim of enlarged diameter, and this projecting rim serves to protect and ward off pressures and blows that might otherwise distort the shoulder portion of the barrel or the bottom disks and result in breaking the waterproofing and joint sealing fillet or filling *a*, of paraffin or other sealing substance. 100 105 110 115 120 125

Such sealing material in melted liquid form is usually introduced into the bottomed container to enter and harden in and seal the annular joint where the top disk fits under the ledge 2, the surplus melted paraffin being poured from the container. This fillet when hard and cool is brittle and liable to become broken and dislodged by distortion or bending of the container body or disks, hence the 5 advantage gained by the formation and structure which reduces to the minimum possibility of such distortion. However, it is not the intention to limit all features of the invention to the presence of such joint sealing 10 deposit or fillet, inasmuch that the presence of the smooth cut inner disk in cooperation with the flanged outer disk, the annular enlarged ledge or shoulder and the inner surface of the expanded barrel end, establish a 15 liquid tight seal that avoids the necessity of the waterproofing seal *a*, possibly except as a factor of precautionary protection.

I have found that it is almost impossible to produce a flanged paper board disk, such as 4, 20 wherein the outer surface of the flange is uniformly smooth and without longitudinal channels or creases that tend to promote liquid seepage from the interior of the container by capillary action or otherwise 25 30 where the flanged disk is overlarge and locked in the expanded end of the paper barrel and seated directly against an annular internal ledge formed in the body by the body expanding operation. Hence, the desirability 35 of employing the seal *a*, for the annular joint within the container between the shoulder and top surface of the flanged disk. I have discovered however that this difficulty caused by the outer surface of the flanged disk is 40 overcome, and certain other advantages are gained, by employing the smooth-cut stiff non-flanged inner disk, in the combination, as hereinbefore described, firmly locked between the shoulder 2, and the flanged disk.

45 In the example shown, the tapered paper barrel, in the form shown by Figs. 1 to 3, is placed on a correspondingly tapered mandrel 10, having an upper end reduced in diameter, and having a flat top die face. The overlong 50 upper end of the barrel 1, projects upwardly beyond this mandrel. The projecting upper end of the paper body can be expanded and contracted to form the ledge 2, and the upper end of enlarged diameter, by suitable mechanism, or the barrel end might be expanded by driving in the various disks by plungers, such as 11, and 11^a, as shown, or otherwise. The plungers 11, 11^a, are flat and horizontal 55 at their working faces to back and support 60 the disks throughout their areas and thus support and drive the same as hereinbefore described, and if so desired said working faces can be rounded or convexed to convex the disks 3, 4, toward the interior of the body by 65 the drag of the edge portions of the disks on the inner surfaces of the paper barrel. The disks will thus be seated and secured in dished inwardly convexed form under constant tension to return to flat form of enlarged diameter with the edge of the disks thus held under tension bearing radially outwardly against the surrounding wall of the paper barrel. In Fig. 3, a crimping or spinning head 12, is shown pressing the two disks 70 75 tightly together and against the end die face of the mandrel and against the ledge 2, and ironing out the outer approximately cylindrical face of the enlarged rim portion 5^a, while completing the tight crimp 5, and exerting downward pressure thereon.

80 What I claim is:—

1. A container embodying a longitudinally tapered sheet paper material body at one end portion expanded to an enlarged diameter and thereby forming an annular enlarged-diameter internal ledge joining the expanded portion with the tapered portion of the body; a stiff imperforate flat-cut paper material disk driven longitudinally through said enlarged end and tightly pressed against said ledge; a flanged paper material disk driven longitudinally through said expanded body end against said first mentioned disk; and a disk locking and supporting crimp between the expanded body end and the flanged disk, whereby the smooth-cut disk is held in against the ledge and the expanded body end is drawn radially and annularly inwardly into liquid tight engagement with the peripheral portions of the two disks.

90

2. A container embodying a paper material body expanded at one end to provide an interior annular ledge; an inner stiff oversize smooth-cut bottom disk driven through said expanded end tightly against said shoulder; an oversize annularly flanged outer paper disk driven through said expanded end tightly against said inner disk; the expanded end of the body being crimped over the flange of the disk and against the flanged disk to lock the disks together and against said ledge and to form the container with a surrounding stiff enlarged rim and a depending bottom rim.

95

3. A container embodying a longitudinally tapered paper body at its bottom end portion having an internal annular ledge; a smooth-cut stiff inner bottom disk driven through said end and seated at its inner side face against said ledge with the cylindrical peripheral edge of said disk in tight sealing engagement with the surrounding inner surface of the body; an annularly-flanged outer bottom disk driven into said body end tightly against said inner disk; and a disk locking crimp forming the container with a bottom seal protecting stiffening annular rim.

100

4. A container embodying a longitudinally tapered paper body at its bottom end portion having an internal annular ledge; a smooth-cut stiff inner bottom disk driven through said end and seated at its inner side face against said ledge with the cylindrical peripheral edge of said disk in tight sealing engagement with the surrounding inner surface of the body; an annularly-flanged outer bottom disk driven into said body end tightly against said inner disk; and a disk locking crimp forming the container with a bottom seal protecting stiffening annular rim.

105

5. A container embodying a longitudinally tapered paper body at its bottom end portion having an internal annular ledge; a smooth-cut stiff inner bottom disk driven through said end and seated at its inner side face against said ledge with the cylindrical peripheral edge of said disk in tight sealing engagement with the surrounding inner surface of the body; an annularly-flanged outer bottom disk driven into said body end tightly against said inner disk; and a disk locking crimp forming the container with a bottom seal protecting stiffening annular rim.

110

6. A container embodying a longitudinally tapered paper body at its bottom end portion having an internal annular ledge; a smooth-cut stiff inner bottom disk driven through said end and seated at its inner side face against said ledge with the cylindrical peripheral edge of said disk in tight sealing engagement with the surrounding inner surface of the body; an annularly-flanged outer bottom disk driven into said body end tightly against said inner disk; and a disk locking crimp forming the container with a bottom seal protecting stiffening annular rim.

115

7. A container embodying a longitudinally tapered paper body at its bottom end portion having an internal annular ledge; a smooth-cut stiff inner bottom disk driven through said end and seated at its inner side face against said ledge with the cylindrical peripheral edge of said disk in tight sealing engagement with the surrounding inner surface of the body; an annularly-flanged outer bottom disk driven into said body end tightly against said inner disk; and a disk locking crimp forming the container with a bottom seal protecting stiffening annular rim.

120

8. A container embodying a longitudinally tapered paper body at its bottom end portion having an internal annular ledge; a smooth-cut stiff inner bottom disk driven through said end and seated at its inner side face against said ledge with the cylindrical peripheral edge of said disk in tight sealing engagement with the surrounding inner surface of the body; an annularly-flanged outer bottom disk driven into said body end tightly against said inner disk; and a disk locking crimp forming the container with a bottom seal protecting stiffening annular rim.
